ELECTRIC LIGHTING SET

Clarence R. Janz, Milwaukee, Wis.

Application November 17, 1941, Serial No. 419,491

2 Claims. (Cl. 173—334)

This invention relates to electric lighting sets, and its general object is to provide a lighting set that is primarily designed for display and ornamental use on a Christmas tree, and especially to bring about a uniform and symmetrical distribution of the lights, as well as to facilitate applying and removing the set with respect to the tree.

A further object is to provide a Christmas tree electric lighting set that includes separable companion units, each having lamp conductors which preferably extend radially from a connector or tap block, the conductors of the respective units being of varying length, so that the units can be assembled in a set having a gradually decreasing width or diameter from the lowermost to the uppermost set, for the lamps to follow the general conical configuration of the tree, it being obvious that trees generally used for Christmas display purposes are of tapered form.

Another object is to provide a Christmas tree electric lighting set that includes a plurality of separable companion units, each having a connector block in which provision is made for not only connecting the lamp conductors in parallel, but each block has cap plug carried conductors connected to contact members within the block, and said contact members have the lamp conductors connected thereto, as well as provide spring contacts for the prongs of the plug of an adjacent unit.

A still further object is to provide a Christmas tree electric lighting unit of the character set forth, that is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing where-in like characters denote like or corresponding parts throughout the several views, and in which:

Figure 1 is a front view of a set assembled from four of my units.

Figure 2 is a perspective view of a connector block provided with a clamp for securing the same to the trunk of a tree.

Figure 3 is a vertical sectional view taken through the block, with a cap plug of the usual construction mounted therein.

Figure 4 is a sectional view taken approximately on line 4—4 of Figure 3, looking in the direction of the arrows.

Figure 5 is a perspective view of one of the contact members or strips of the connector block, with the lamp and cap plug conductors connected thereto.

Figure 6 is a perspective view illustrating the clamping ring in use for securing lamp conductors to a lamp of the tree.

Figure 7 is a view illustrating a coiled resilient type sheathing that may be used on the conductors for the cap plugs.

Referring to the drawing in detail, it will be noted that each unit includes a connector or tap block having a hollow body of rectangular form in the form shown, and the body is made up of a pair of identical separable half sections formed from any suitable insulating material. The sections are secured together by bolt and nut connections 2 to provide front, rear, top, bottom and side walls. At the juncture of the side wall portions of the sections, with each other, it will be noted as best shown in Figure 2 that said side wall portions are recessed to provide conductor passage openings 3, there being three openings in each side wall, in the form shown, and the portions of the sections that provide the bottom wall are likewise recessed to provide a conductor passage opening 4, while each of the portions that provide the top wall have a slot 5 therein, and the slots extend along the longitudinal center of the portions and upon opposite sides of inwardly extending projections 5'.

The front and rear walls are of greater thickness than that of the side walls, as will be noted from Figure 4, and arranged along the height of the inner faces of the front and rear walls are grooves 6 that have mounted therein spring conductor and contact strips 7 which have the lower ends seated within the bottom wall, as shown in Figure 3, and the upper end portions of the strips 7 are looped inwardly and downwardly to provide flexible contact arms 8 arranged to underlie the slots 5, and to normally engage the projections 5', for disposal in the path of the prongs 9 of a cap plug 10 of the usual construction, so that the prongs 9 contact the arms 8 for connecting companion units together, as will be apparent.

Each of the units likewise include six lamp sockets 11 in the form shown, and a pair of conductors 12 is provided for each socket. One conductor of each socket is connected to one

strip 7 while the other conductor is connected to the other strip, as best shown in Figure 4, and these conductors are soldered or otherwise electrically fixed to the strips, as indicated in Figure 5. By that construction, it will be obvious that the sockets are connected in parallel, so that in the event any one of the lamp bulbs 13 should become burned out, such will not effect the remaining bulbs in the unit.

The cap plug of each unit has one of the ends of a pair of conductors 14 connected thereto in the usual manner, and one of the conductors 14 has its opposite end connected to one contact member or strip 7, while the other conductor 14 has its opposite end connected to the other strip, the conductors 14 being likewise soldered or otherwise electrically fixed to the strips. While the conductors 14 have the usual fabric sheathing 15 thereon, they may have coiled resilient sheathing 16 thereon, as shown in Figure 7, so that the cap plug will be held in proximity to the connector block when the unit is not in use. That feature facilitates packing the units in boxes or the like for storage or sale purposes.

While a set may consist of any number of units, it depending upon the height of the tree, it will be noted from Figure 1 that I have illustrated four units assembled or connected together for disposal in superimposed relation, and that the conductors 12 of the respective units shown decrease in length from the lowermost to the uppermost unit, so that the set will follow the taper of the usual tree used for Christmas display purposes, and when the set is applied to the tree, the conductors 12 can be arranged in any desired manner or design, such as for example to radiate in substantially equidistantly spaced relation from the connector block, for disposal of the lamp bulbs adjacent the ends of the branches of the tree to bring about a symmetrical distribution of the bulbs, and thus materially enhance the beauty of the display.

In order to secure the connector blocks to the trunk of the tree, I provide clamping members which include attaching ears 17 that are fixed to the rear wall of the block by the bolts of the bolt and nut connections 2, and formed on the ears 17 are spring arms 18 to embrace the trunk, as will be apparent. The outer end portions of the arms are outwardly flared to facilitate applying the same to the trunk.

I also provide split spring rings 19 for disposal about the limbs of the tree, as well as the conductors 12 for securing the latter to the limbs, as clearly shown in Figure 6.

It is thought from the foregoing description

that the advantages and novel features of the invention will be readily apparent.

It is to be understood that changes may be made in the construction and in the combination and arrangement of the several parts, provided that such changes fall within the scope of the appended claims.

What I claim is:

1. In a device of the character described, an elongated hollow body having slots in one end adapted to receive the prongs of a plug connector and a plurality of longitudinally spaced openings in the side walls for the passage of wires, the bottom of the hollow body having a wire receiving opening, the front and rear of the said hollow body having a groove extending the full length of the body interiorly thereof, a pair of connection members mounted within the hollow body, each of the said members including a straight relatively long body strip fitted within and extending the full length of each longitudinal groove in the body and having one end portion bent U-shaped to provide a relatively short parallel contact arm disposed to project inwardly of the body and protrude from the groove to contact the plug prongs, and a series of pairs of wires electrically connected to the body strip in longitudinally spaced relation.
2. In a device of the character described, an elongated hollow body having slots in one end adapted to receive the prongs of a plug connector and a plurality of longitudinally spaced openings in the side walls for the passage of wires, the bottom of the hollow body having a wire receiving opening, the front and rear of the said hollow body having a groove extending the full length of the body interiorly thereof, a pair of connection members mounted within the hollow body, each of the said members including a straight relatively long body strip fitted within and extending the full length of each longitudinal groove in the body and having one end portion bent U-shaped to provide a relatively short parallel contact arm disposed to project inwardly of the body and protrude from the groove to contact the plug prongs, the straight ends of the said body strips projecting into and tightly seated in the bottom wall of the hollow body, a pair of terminal wires passing through the bottom opening of the hollow body and connecting with the lower ends of the respective body strips, and a series of pairs of wires extending through the openings in the side walls of the hollow body and electrically connected with the body strip at longitudinally spaced intervals.

CLARENCE R. JANZ.
